UNITED STATES PATENT OFFICE

108,998

DESIGN FOR A CABINET FOR COMBINATION RADIO, PHONOGRAPH, AND MICROPHONE

Leonard A. Herzig, Brooklyn, N. Y., assignor to
Conquest Alliance Co., Inc., New York, N. Y., a
corporation of New York

Application June 15, 1937, Serial No. 69,856

Term of patent 14 years

To all whom it may concern:

Be it known that I, Leonard A. Herzig, a citizen of the United States, residing at Brooklyn, State of New York, have invented a new, original and ornamental Design for a Cabinet for Combination Radio, Phonograph, and Microphone, of which the following is a specification, reference being had to the accompanying drawing forming part thereof, and which is a perspective view of a cabinet for a combination radio, phonograph and microphone embodying the invention.

The right-hand end of the cabinet, as viewed in the drawing, is similar to the opposite end which is shown to the left of the drawing, while the rear of the cabinet (not shown) is flat and of plain design.

I claim:

The ornamental design for a cabinet for combination radio, phonograph, and microphone substantially as shown and described.

LEONARD A. HERZIG.
